UNITED STATES PATENT OFFICE.

RUFUS J. HUTCHINS, OF MIDDLETOWN, OHIO.

WATER HEATER.

1,421,692.

Specification of Letters Patent. Patented July 4, 1922.

Application filed November 10, 1921. Serial No. 514,421.

To all whom it may concern:

Be it known that I, RUFUS J. HUTCHINS, a citizen of the United States, residing at Middletown, in the county of Butler and State of Ohio, have invented certain new and useful Improvements in Water Heaters, of which the following is a specification, reference being had therein to the accompanying drawing.

10 This invention relates to water heaters and is in the nature of an improvement on the water heater of the application for patent filed by me July 18, 1921, Serial No. 485,602.

15 In a water heater of this kind a relatively small burner will maintain the water at the desired temperature when no water is withdrawn or small quantities of water are withdrawn, but when large quantities of water are withdrawn a relatively large burner is required. If the large burner is utilized when small quantities of water are withdrawn more heat is generated than is necessary and there is a waste of fuel.

20 25 One object of the present invention is to provide a heater which will maintain a constant supply of hot water ready for instant use and which will accomplish this without wasting fuel.

30 A further object of the invention is to provide such a heater having two heating devices with separate circulation systems which will be operated according to the amount of water withdrawn.

35 Other objects of the invention will appear as the device is described in detail.

In the accompanying drawings Fig. 1 is a vertical sectional view taken centrally through a water heater embodying my invention; Fig. 2 is a section taken on the line 2—2 of Fig. 1; Fig. 3 is a vertical sectional view of a water heater embodying the invention in a slightly modified form; Fig. 4 is a section taken on the line 4—4 of Fig. 3; Fig. 5 is a section taken on the line 5—5 of Fig. 3; and Fig. 6 is a sectional detail view of the safety valve.

In these drawings I have illustrated one embodiment of my invention, together with a slight modification thereof, and have shown the same as comprising a heater proper, which is enclosed within a casing 1, and a water reservoir, or tank 2 which in the present instance is supported directly above the heater. The tank is connected with a suitable source of water supply, such as a

city main, by a pipe 3 which preferably discharges into the tank at a point near the bottom thereof. An outlet pipe 4 leads from the tank to the distribution system. Inasmuch as the tank is in open communication with the source of supply, which, of course, is under pressure, it will be apparent that the water will flow from the tank whenever a faucet in the distribution system is opened. A safety valve 5, Fig. 6, is interposed between the outlet pipe 4 and the tank 2, this valve being of substantially the construction shown and described in the above mentioned application.

When the tank is standing idle, that is, no water is being withdrawn from it, very little heat is required to maintain the water therein at the desired temperature and even when small quantities of water are being withdrawn from the tank and corresponding quantities of cold water introduced into the same, a relatively small burner will furnish all the heat that is necessary to maintain the temperature at the desired degree. I have, therefore, provided a heating device comprising a heating element 7 which, as here shown, is in the form of a double cone shaped receptacle and beneath which is arranged a burner 8 connected by a pipe 9 with a suitable supply of gas. Preferably this heating device is normally operative. That is, the burner burns continuously but the flame is reduced normally to a very low point. The heating element 7 is connected with the tank by means of a pipe 10 leading from the bottom of the tank to the bottom of the heating element and by a pipe 11 leading from the top of the heating element into the tank and preferably opening into the tank at a point near the top thereof. These pipes and the heating element itself comprise a separate circulation system for the normally operative heating device and it will be apparent that the heat applied to the heating element will cause a slow circulation of the water through the circulation system, thus maintaining the water in the tank at the desired temperature.

If water is withdrawn from the tank in sufficient quantities to materially affect the temperature of the water in the tank, the low normal flame of the burner 8 would not restore the temperature with sufficient rapidity and I prefer to provide means for automatically increasing the heat applied to the heating element 7 when the tempera-

ture of the water in the tank falls below a predetermined degree. To this end the flow of gas to the burner 8, through the pipe 9, is controlled by a valve 12 which is normally open to a sufficient extent to maintain the desired normal flame at the burner 8. This valve 12 is controlled by a thermostat 13 which extends into the tank and is set to open the valve 12 when the water in the tank falls below a predetermined temperature, thus admitting additional gas to the burner 8 and causing the temperature to be quickly restored. When the temperature again rises the thermostat restores the valve 12 to its normal position and the flame at the burner 8 is reduced to its normal size. The valve 12 and thermostat 13 may be of any suitable construction and as thermostatically controlled valves are well known in the art it is not thought necessary to here illustrate or describe the same in detail.

When water is being withdrawn from the tank in large quantities the heating device, 7, even when the burner 8 is operating at full capacity, will be insufficient to maintain the water at the desired temperature. I have, therefore, provided a second heating device which consists of a heating element, or coil, 14 arranged in the upper part of the casing 1 of the heater and preferably coiled about a cylindrical housing 15 within which are the burner 8 and heating element 7. Arranged beneath the heating coil 14 is a burner 16 of large capacity which is connected with a source of gas supply by a pipe 17. This burner is normally inoperative and is ignited only when the temperature of the water in the tank falls to such an extent that the first mentioned heating device can not restore it to normal. To this end the flow of gas through pipe 17 to the burner 16 is controlled by a thermostatically operated valve 18, the thermostat 19 of which extends into the tank and is set to operate at a temperature somewhat lower than the temperature at which the thermostat 13 will operate. When the temperature of the water falls to this lower degree the thermostat 19 will operate the valve 18 and the gas flowing to the burner 16 will be ignited by the normally operative burner 8, which acts as a pilot burner for the large, or main, burner 16. The heating coil 14 is connected with the tank 2 by a pipe 20 leading from the bottom of the tank to the lowermost winding of the coil and by a pipe 21 leading from the uppermost winding of the coil to the tank and preferably discharging into the tank near the upper end thereof. Thus the heating coil and the pipes 20 and 21 form a separate circulation system for the main heating device.

The operation of the device will be readily understood from the foregoing description and it will be apparent so long as the amount of water withdrawn from the tank is not

sufficient to materially lower the temperature of the water within the tank the normally operative burner will suffice to maintain the desired temperature in the tank, but if the temperature falls to such an extent that the normal heat will not restore it with sufficient quickness the thermostat 13 will operate the valve 12 to admit additional gas to the burner 8, thus increasing the heat applied to the heating element 7 and restoring the temperature within the tank. It is only when water is withdrawn from the tank in such quantities that the temperature is lowered to such an extent that the burner 8 when operating at full capacity can not restore the same with sufficient quickness, that the thermostat 19 will operate to render the main burner 16 operative, and thus through the medium of the second circulation system and the heating coil quickly heat the water within the tank.

While I have shown the two circulation systems as wholly independent one from the other, in Fig. 1, it is possible for these two circulation systems to communicate with the tank through the same pipes and yet maintain their separate operation and in Fig. 3 I have shown such an arrangement. As there shown, a pipe 22 leads from the bottom of tank 1 to the bottom of the heating element 7 and this same pipe is connected, by means of a T-shaped joint 23 with the lower winding of the heating coil 14. The upper winding of the heating coil 14 is connected by a pipe 24 with the tank and the pipe 25 which leads from the top of the heating element 7 is connected with the pipe 24 above the coil. In this manner only two pipes lead into the tank but the circulation systems maintain their separate connections and the operation is exactly the same as that described in connection with the device in Fig. 1.

While I have shown and described certain embodiments of my invention I wish it to be understood that I do not desire to be limited to the details thereof as various modifications may occur to a person skilled in the art.

Having now fully described my invention what I claim as new and desire to secure by Letters Patent, is:

1. In a water heater, a tank connected with a source of water supply, a normally operative heating device, a circulation system connecting said heating device with said tank, a normally inoperative heating device, a separate circulation system connecting the last mentioned heating device with said tank, and means for rendering said last mentioned heating device operative when the water in said tank falls below a predetermined temperature.

2. In a water heater, a tank connected with a source of water supply, a normally operative heating device, a circulation sys-

tem connecting said heating device with said tank, a normally inoperative heating device, a separate circulation system connecting the last mentioned heating device with said tank, and means for supplying additional heat to the first mentioned heating device when the water in said tank falls below a predetermined temperature and for rendering said last mentioned heating device operative when the water in said tank falls below another predetermined temperature.

3. In a water heater, a tank connected with a source of water supply, a heating element, a circulation system connecting said heating element with said tank, a burner for said heating element, means controlled by the temperature of the water in said tank for controlling said burner, a second heating element, a separate circulation system for said second heating element, a burner for said second heating element, and means controlled by the temperature of the water in said tank for controlling the last mentioned burner.

4. In a water heater, a tank connected with a source of water supply, a heating element, a circulation system connecting said heating element with said tank, a burner for said heating element, means controlled by the temperature of the water in said tank for controlling said burner, a second heating element, a separate circulation system for said second heating element, a burner for said second heating element, and means controlled by the temperature of the water in said tank for controlling the last mentioned burner, one of said controlling means being set to operate at a temperature lower than that at which the first mentioned controlling means will operate.

5. In a water heater, a tank connected with a source of water supply, a heating element, a burner for said heating element, means controlled by the temperature of the water in said tank for controlling the operation of said burner, a second heating element, a burner for said second heating element, and means controlled by the temperature of the water in said tank for controlling the operation of said second burner, and separate circulating systems connecting the respective heating elements with said tank.

6. In a water heater, a tank connected with a source of water supply, a heating element, a burner for said heating element, means controlled by the temperature of the water in said tank for controlling the operation of said burner, a second heating element, a burner for said second heating element, and means controlled by the temperature of the water in said tank for controlling the operation of said second burner, and wholly independent circulating systems connecting the respective heating elements with said tank.

7. In a water heater, a tank, a heater comprising a casing arranged below said tank, a heating element arranged within said casing, a pipe leading from the bottom of said tank to the bottom of said heating element, and a second pipe leading from the top of said heating element to the upper portion of said tank, a heater arranged beneath said heating element, a valve to control the flow of gas to said burner, a thermostat arranged within said tank and operatively connected with said valve, a heating coil arranged within said casing, a pipe leading from the lower portion of said tank to the lower winding of said coil, a second pipe leading from the upper winding of said coil to the upper portion of said tank, a burner arranged beneath said coil, a valve to control the flow of gas to the last mentioned burner, and a thermostat arranged within said tank and operatively connected with the last mentioned valve.

8. In a water heater, a tank connected with a source of water supply, a heating coil, pipes connecting the respective ends of said coil with said tank, a burner arranged beneath said coil, means controlled by the temperature of the water in said tank to control said burner, a casing arranged within said coil, a heating element within said casing, pipes connecting said heating element with said tank, a normally operative burner arranged beneath said heating element, and means controlled by the temperature of the water in said tank to regulate the flow of gas to the last mentioned burner.

In testimony whereof I affix my signature hereto.

RUFUS J. HUTCHINS.
